UNITED STATES PATENT OFFICE

CHARLES H. SCHURR, OF CLEVELAND, OHIO, ASSIGNOR TO THE LEES-BRADNER COMPANY, OF CLEVELAND, OHIO, A CORPORATION OF OHIO

TOOL FOR FINISHING GEAR TEETH

Application filed January 5, 1927. Serial No. 159,092.

This invention relates to finishing tools for gear teeth or the like.

The invention relates particularly to finishing tools which are themselves of gear form, and which finish the working faces of gear teeth or the like while running in mesh therewith.

One of the objects of my invention is to provide an improved finishing tool in general 10 of gear form.

Another object is to provide a finishing tool suitable for use in carrying out the gear finishing method disclosed in my Patent No. 1,642,179, Sept. 13, 1927.

15 Other objects will be apparent.

The invention is fully disclosed in the following description and accompanying drawings in which,

Fig. 1 is a view of a part of a tool of gear 20 form embodying my invention, showing the longitudinal ends of the tool teeth on one side or face of the tool;

Fig. 2 is an elevational view of a tool tooth in one form, taken from the plane 2—2 of 25 Fig. 1;

Fig. 3 is a cross-sectional view taken from the plane 3—3 of Fig. 1;

Fig. 4 is a partial sectional view, taken from the plane 4—4 of Fig. 1;

30 Figs. 5 to 12 inclusive, are views similar to Fig. 3 showing modifications;

Figs. 13 and 14 are views similar to Fig. 4 showing modifications.

My invention is disclosed as applied to the 35 finishing of gear teeth and when so applied, I prefer the form shown in Figs. 1 to 4 inclusive. The gear form tool, Fig. 1, has teeth 1—1, the faces 11 and 12 of which are accurate to a high degree as to profile, spacing around the gear, and concentricity. I prefer to produce such teeth by roughing them out in any well known and suitable manner and then finishing them by grinding on a generating grinder, but other methods may be employed.

40 The ends of the teeth, as viewed in Fig. 1, are then chamfered along their curved edges as at 13, 14. In Fig. 1, the chamfers appear upon one end only of the teeth, but the other ends not shown may similarly be chamfered, and 45 if viewed as in Fig. 1, would appear the same

as in Fig. 1. The chamfers 13, 14 of Fig. 1 are plainly shown in Figs. 2, 3 and 4, as are also the chamfers 15, 16 on the other ends of the teeth. The chamfers 13, 14, 15 and 16 may be formed on the teeth by any suitable 55 method or means, but I prefer to grind them by a generating grinding machine.

When grinding the faces 11 and 12 of the gear teeth 1, and the chamfers 13, 14, 15, and 16, any suitable means or method may be employed, but when grinding them in the preferred manner by means of generating gear grinders as above mentioned, I prefer to employ the method described in my co-pending application, Serial No. 49,282, filed Au- 60 gust 10, 1925. According to that method the gear-to-be-ground, in this case the tool, is given a rolling movement into and out of engagement with the planular face of a grinding wheel. The gear or gear tool rolls 65 on a pitch circle thereof and the rotational axis thereof describes a plane. The rotary planular faced grinding wheel is positionally adjustable about an axis perpendicular to said plane to adjust the helical angle at which it grinds.

In producing a tool of the present invention, the grinding wheel may first be adjusted to zero helical angle and the faces 11 of the teeth may be ground by rolling the gear or tool as above described. The tool 70 may then be turned end for end and the faces 12 ground. The planular face of the grinding wheel may then be adjusted to a suitable

helical angle and helical tooth faces such as the faces 13 may be ground on each of the teeth and will constitute chamfers. The tool 75 may then be reversed end for end and in a like manner helical faces 15 constituting chamfers may be ground. The planular face of the grinding wheel may then be adjusted to the same or similar helical angle opposite to the first helical angle in the sense of right and left hand and helical faces 14 may be 80 ground constituting chamfers. The gear may then be reversed end for end and helical faces 16 may be ground constituting chamfers.

85 The chamfers 13 and 15 therefore may be, as illustrated in Figs. 1 to 4 inclusive, fragmentary portions of the opposite faces 90 of a helical gear tooth which is, say, right 95 100

hand; and similarly the chamfers 14 and 16 may be fragmentary portions of the opposite faces of a left hand helical gear tooth.

The tips or extreme outer portions of the teeth, radially considered, terminate in tip surfaces 10 and preferably these tip surfaces are not chamfered where they intersect the end surfaces of the teeth; the chamfers 13, 14, 15 and 16 thus extend all the way out to the tip surface, (and do not stop short thereof as they would if the tip surfaces were chamfered), and therefore may be coextensive with the curved side faces of the tool teeth, thus providing a working chamfer on the tool long enough to work over the whole working face of the work gear teeth.

The exact profile of the chamfers, as viewed in Fig. 3, may be different in different cases in accordance with the different conditions met in carrying out the method in which the tool is used, such conditions for instance as the structure of the metal of the work gear to be finished, its composition, hardness, etc., the amount of metal to be dealt with on the surfaces to be finished of the work gear teeth when they are left over-size by the roughing-out operation, etc., the rate of feed of the tool with respect to the work gear teeth longitudinally, the fineness of the resulting finish desired, etc. In this connection, the chamfer may have any of the forms shown in Figs. 3, 5 to 12 inclusive.

In Fig. 3 the chamfers 13, 14 and 15, 16 are on opposite ends of the tool tooth. In Fig. 5, the chamfers 15, 16 are placed intermediate of the ends. With this form, relatively thin work gears may be finished without having to move the tool and work gear relatively over the entire width of face of the tool, that is, over the entire longitudinal length of the tool teeth, but at the same time the tool can be relatively thick and have teeth of relatively great length for strength. In Figs. 1 to 5 inclusive, two sets of chamfers 13, 14 and 15, 16 are provided, in which forms the tool is adapted to work the gear teeth in both directions longitudinally, passing over them two or more times. In the forms, Figs. 6 to 12 inclusive, chamfers on only one end of the tool tooth are shown, and such tools are intended to finish the gear teeth in one passage thereover, or by repeated passes in the same direction. In Fig. 6, by having the reduced portion 4 intermediate of the ends of the tool tooth, the working portion of the tool tooth will run out free from the work gear teeth with relatively small longitudinal movement. In Fig. 7 a chamfer is shown of approximately the same degree of obtuseness as the chamfers of Figs. 1 to 6 inclusive. In Fig. 8, a less obtuse chamfer is shown. In Fig. 9, a more obtuse chamfer is shown. In Fig. 10 the chamfer is curved convexly. In Fig. 11, the chamfer is curved concavely. In Fig. 12, the chamfer is even more obtuse than in Fig.

9, and this figure represents a chamfer so obtuse that it is substantially at right angles to the longitudinal direction of the tooth, that is it has the maximum obtuseness possible or practicable.

In Fig. 13 a modification is shown in which the obtuseness of the chamfer is substantially that of Fig. 12. In this modification the face of the tool is recessed or cut away as at 5-5, leaving raised portions 6-6. The working portions of the tool teeth may be renewed by grinding the faces 7-7 of the tool in a plane or substantially in a plane. The elevated portions 6-6 and recessed or cut away portions 5-5 may also be employed with the preferred form of Figs. 1 to 4 inclusive above described, when it is desired to renew the chamfers 13, 14 and 15, 16 thereof, and when repeated renewal makes it desirable to remove some of the end or ends of the tool tooth; for example, in Fig. 3 if the chamfers 13, 14 have been renewed, say by grinding, until they lie in positions represented by the lines 8-8, it may be desirable to grind off or otherwise remove the end of the tooth to the plane indicated by the line 9.

In the modification shown in Fig. 14, one end of the tooth has the chamfer 16, and the other end has the chamfer of Fig. 12.

My invention is not limited to the particular modifications shown. My invention embraces in its scope many forms of tool not shown which are in general of gear form, and are suitable or adaptable to finish gears.

My invention is not limited in its application, to tools for finishing gears. The method of my above mentioned application for example, is as shown therein, applicable to shapes other than circular and to parts other than gears, and the invention of the present application embraces in its scope tools suitable for finishing all such and similar articles. In the claims therefore the expression "in general of gear form" is to be taken as meaning a tool which has such form that it meshes with the article which it finishes in the general manner of one gear meshing with another; or that the tool has teeth or other projections and grooves or recesses which fit or are conjugate to corresponding grooves or recesses and teeth or projections on the article being finished and with which it in consequence runs in mesh while finishing it.

My invention is applicable to the gear finishing method disclosed in my Patent No. 1,642,179, above referred to in which the gear to be finished and the tool are run in mesh with each other and fed axially relatively to each other as described therein, but my invention is not limited to use with this method.

In the claims, I refer to the "axial end faces" of the teeth of the tool of my invention and these faces will be understood to be the faces defining the extent of the teeth in the direction of the gear axis.

I claim :

1. A finishing tool for gears or the like, in general of gear form, the teeth of which have end surfaces and curved side faces and which are chamfered on the edges formed by the intersection of said surfaces and faces. 5
2. A finishing tool for gears or the like, in general of gear form, the teeth of which have end surfaces and curved side faces and which are chamfered on those edges only which are formed by the intersection of said surfaces and faces. 10
3. A finishing tool for gears or the like, in general of gear form, the teeth of which have end surfaces, curved side faces and tip surfaces, edges at the intersections of the end surfaces with the side faces, and edges at the intersections of the end surfaces with the tip surfaces, and of these edges, the former only 15 being chamfered. 20
4. A gear re-working tool, in general of gear form and having gear form teeth some of which at the longitudinal termination of the curved faces thereof are chamfered to provide working edges adapted to displace and correctively redistribute the material composing the tooth faces of the gear-to-be-worked when the tool is rolled in mesh with the gear and concurrently fed longitudinally 25 over the length of the gear teeth. 30
5. A gear re-working tool, in general of gear form and having gear form teeth some of which are provided each with a spur tooth face portion and a helical tooth face portion, the two face portions intersecting in a working edge adapted to displace and correctively redistribute the material composing the tooth faces of the gear-to-be-worked when the tool is rolled in mesh with the gear and concurrently fed longitudinally over the length of the gear teeth. 35 40
6. A gear re-working tool, in general of gear form and having gear form teeth some of which are provided each with a spur tooth face portion and a plurality of helical tooth face portions, the helical portions intersecting the spur portion in a plurality of working edges adapted to displace and correctively redistribute the material composing the tooth faces of the gear-to-be-worked when the tool is rolled in mesh with the gear and concurrently fed longitudinally over the length of the gear teeth. 45 50
7. A gear re-working tool, in general of gear form and having gear form teeth some of which are provided each with a plurality of spur tooth face portions and a plurality of helical tooth face portions, the spur portions being intersected by certain ones of the helical portions in a plurality of working edges adapted to displace and correctively redistribute the material composing the tooth faces of the gear-to-be-worked when the tool is rolled in mesh with the gear and concurrently 55 60 65

fed longitudinally over the length of the gear teeth.

8. A toothed tool in general of gear form some of the teeth of which are provided each with a working edge, the shape and position on the tooth of which are determined by the intersection of an involute spur tooth face and an involute helical tooth face successively produced on the tooth. 70
  9. The method of producing a tool of gear form and provided with working edges on the teeth thereof adapted to displace and redistribute the material of the working faces of the teeth of a gear when rolled in mesh therewith and concurrently fed axially thereover which includes producing tool teeth having side faces and axial end faces intersecting in edges and then removing some of the material of the tooth along the edges formed by the intersections of the end and side faces. 75 80 85
  10. The method of producing a tool of gear form and provided with working edges on the teeth thereof adapted to displace and redistribute the material of the working faces of the teeth of a gear when rolled in mesh therewith and concurrently fed axially thereover which includes producing tool teeth having curved side faces and axial end faces intersecting in curved edges and then removing some of the material from the curved edges to thereby form other faces intersecting the said curved faces and end faces. 90 95
  11. A toothed tool in general of gear form, the teeth of which have side faces and axial end faces joined along a surface portion disposed inwardly with respect to the edge which would be formed by the said end and side faces if produced to an edge of intersection. 100
  12. The method of producing a tool in general of gear form, which includes producing tool teeth having side and axial end faces intersecting in edges and then removing some of the material from said faces adjacent said edges. 105
  13. The method of producing a tool in general of gear form, which includes producing tool teeth having each a side face and an axial end face intersecting in an edge and then removing some of the material of said faces adjacent and along said edge. 110 115
  14. The method of producing a tool in general of gear form, which includes producing tool teeth having side and axial end faces intersecting in edges and then removing the said edges. 120
- In testimony whereof, I have hereunto signed my name.
